FIG. 2

INVENTOR
Frank F. Eno
BY Richard P. Elliott
ATTY.

UNITED STATES PATENT OFFICE.

FRANK F. ENO, OF BOSTON, MASSACHUSETTS, ASSIGNOR TO ENO WELT SHOE COMPANY, A CORPORATION OF MASSACHUSETTS.

BOOT AND SHOE.

1,110,121.

Specification of Letters Patent.

Patented Sept. 8, 1914.

Application filed May 7, 1914. Serial No. 837,054.

To all whom it may concern:

Be it known that I, FRANK F. ENO, a citizen of the United States, residing in Jamaica Plain district, city of Boston, 5 county of Suffolk, State of Massachusetts, have invented certain new and useful Improvements in Boots and Shoes, of which the following is a specification, reference being had to the drawings accompanying 10 the same and forming a part thereof.

My invention relates to boots and shoes and the method of manufacturing the same.

The objects of my invention are to make a boot or shoe wherein means are provided 15 for lasting and securing the upper to the inner sole, which means consists of securing a strip or welt of material to the inner sole so that the inwardly extending edge of the strip or welt will be free, and of thereafter 20 lasting and securing the upper to the inwardly extending portion of the strip or welt.

A further object is to secure a welting strip to the inner sole and upper of the shoe 25 by fastenings, such as stitching, riveting, tacking, or the like, which fastenings extend through the welting-strip, the upper and lining, where there is a lining, and said first-mentioned strip or welt, so that the 30 welting-strip extends outwardly beyond the edges of the shoe upper a sufficient distance so that the outer sole may be secured to said welting-strip by stitching, riveting, nailing, or other securing means.

35 In the drawings accompanying this specification—Figure 1 represents a side elevation of a boot or shoe made in accordance with the method disclosed herein; and Fig. 2 is a section showing the method of securing the upper to the inner sole and of securing 40 the outer sole to the upper.

In the drawings, 1 represents the upper of a boot or shoe, and 2 the outer sole thereof. The outer sole and upper are united 45 through the medium of the inner-sole 3 and the strip or welt 4 secured to it, preferably by the stitching 5, but other suitable fastening means may be used when found desirable. This strip or welt 4 has an inwardly 50 extending free portion, and in the process of assembling the upper 1 and the inner-sole 3 by the process of lasting, the edge of the upper 6 is drawn over the strip or welt 4 so that its edge may be fastened to the said 55 strip or welt 4 by means of tacks, nails or

rivets 7. Other means of fastening, such as stitching through the upper and the free inwardly extending edge of the strip or welt 4 may be employed.

After the upper 1 and the inwardly extending edge of the strip or welt 4 are secured together, a welting-strip 8 is thereafter secured to the upper and the strip or welt 4, preferably by stitching or by other suitable fastening means, so as to leave the 60 edge 10 of the welting-strip 8 extending outwardly beyond the body of the shoe upper a sufficient distance so that thereafter the outer sole 2 may be united to the welting-strip 8 by any suitable fastening means, 70 preferably by stitching, thus uniting the inner sole, outer sole and upper firmly together in a completed shoe.

In the manufacture of boots and shoes by this process it is usual to fill the space 11 75 by any suitable filling means such as is commonly used in the manufacture of boots and shoes.

I do not confine myself to the exact size and form of the various parts, or the exact location of the fastening means for fastening the various parts together, or the type of fastening means used, which in the illustration consists of stitching and tacks, as any other suitable means for fastening the 80 various parts together may be used, or the form and size of the parts may be varied, as desired. Furthermore, I do not limit my invention to a boot of the type illustrated, as my invention is equally applicable to 85 what is known as oxfords, low shoes, pumps, slippers, and other types of footwear.

What I claim is—

1. A boot or shoe arranged for the subsequent attachment of a second welt and an 95 outer sole, consisting of an inner sole, a welt or strip of material secured to the outer face of the inner sole by fastening means located in close proximity to the outer edge of both such inner sole and welt, the 100 inner edge of said welt being free from such inner sole, and an upper permanently secured to the free inwardly extending portion of said welt or strip.

2. In a boot or shoe, the combination of an 105 upper, an inner sole, a strip or welt of material secured to the edge of the inner sole so as to leave said welt with a free inwardly extending portion, fastening means securing the upper to said strip or welt, and a 110

2
second welt strip secured by additional fastening means to said first mentioned welt or strip and upper.

3. In a boot or shoe, the combination of
5 an inner sole, a strip or welt of material se-
cured to the outer face of the inner sole in
close proximity to the outer edge of both
the welt and inner sole so as to leave the
inner edge of such welt free from the inner
10 sole, a shoe upper, fastening means for se-
curing said upper to the free inwardly ex-
tending portion of said strip or welt, a sec-
ond welt strip, additional means for fas-

tening such second welting strip to the up-
per and said first-mentioned strip or welt,
an outer sole and means for fastening it to
said second welting strip.

In testimony whereof, I have hereunto
set my hand, in the presence of two subscrib-
ing witnesses, this the 5th day of May, A. D. 20
1914.

FRANK F. ENO.

Witnesses:

P. W. PEZZETH,
H. M. KELSO.
